United States Patent Office

Des. 197,696
Patented Mar. 17, 1964

197,696

BRUSH

Joseph Vallis, 448 Spadina Road, Toronto,
Ontario, Canada

Filed Sept. 9, 1960, Ser. No. 62,088

Term of patent 14 years

(Cl. D9—2)

Fig. 1.

Fig. 2.

Fig. 3.

FIG. 1 is a perspective view of a brush showing my new design;

FIG. 2 is an end elevational view thereof; and

FIG. 3 is a sectional view taken on line 3—3 of FIG. 1.

The essential features of my design reside in the bristles which are shown in full lines on the drawing.

I claim:

The ornamental design for a brush, as shown and described.
